DESIGN FOR A VELOCIPED FORK

Harold L. van Doren, Toledo, and John G. Rideout, Perrysburg, Ohio, assignors to The American-National Company, Toledo, Ohio, a corporation of Ohio

Application February 5, 1936, Serial No. 60,992

Term of patent 7 years

To all whom it may concern:

Be it known that we, Harold L. van Doren and John G. Rideout, citizens of the United States of America, residing at Toledo and Perrysburg, in the counties of Lucas and Wood, respectively, and State of Ohio, have invented a new, original, and ornamental Design for a Velocipede Fork, of which the following is a specification, reference being had therein to the accompanying drawing, forming a part thereof, wherein:

Figure 1 is a side elevation of a velocipede fork showing our new design;

Figure 2 is a front elevation thereof;
Figure 3 is a top plan view thereof; and
Figure 4 is a cross sectional view taken substantially on the line 4—4 of Figure 1.

We claim:

The ornamental design for a velocipede fork substantially as shown.

HAROLD L. VAN DOREN.
JOHN G. RIDEOUT.
